UNITED STATES PATENT OFFICE.

JOHN BELL SHELTON, OF TACOMA, WASHINGTON, ASSIGNOR OF ONE-HALF TO PETER DAVID, OF TACOMA, WASHINGTON.

FREIGHT AND STOCK CAR.

1,143,234.

Specification of Letters Patent. Patented June 15, 1915.

Application filed September 26, 1914. Serial No. 863,691.

To all whom it may concern:

Be it known that I, JOHN BELL SHELTON, citizen of the United States, residing at Tacoma, county of Pierce, State of Washington, have invented a certain new and useful Improvement in Freight and Stock Cars, and declare the following to be a full, clear, and exact description of the same, such as will enable others skilled in the art to which it pertains to make and use the same, reference being had to the accompanying drawings, which form a part of this specification.

My invention relates to a combined freight and stock car shown in the accompanying drawings and more particularly pointed out in the following specification and claims.

The object of my invention is an improvement in the general construction of adjustable double deck cars, in which two separate compartments are provided for shipping small stock, and which may be adapted for carrying ordinary freight by lowering the adjustable deck that it may rest upon the platform of the car.

Cars of this character are usually provided with a central longitudinal shaft extending their entire length and fitted on the outside with suitable means for manually rotating the shaft, whereby the deck may be raised or lowered as required. This form of construction being expensive one feature of my invention is to reduce the cost by employing a relatively short shaft located entirely within the car, the ends of the shaft being threaded and fitted respectively with a traveling arm connected with the adjustable platform by chains or cables, the latter being carried and supported by suitable sheaves attached to the car frame. Mounted upon the shaft is a ratchet lever adapted to manually rotate it that the platform may be adjusted.

Another feature of the invention consists in the means employed for independently supporting the movable platform when raised, said means being adapted to bind the side walls of the car to the platform thereby providing a more rigid structure and insuring against the spreading of the walls due to the load carried.

Another feature of the invention consists in the manner of connecting suitable so-

called "hog doors" to the underside of the platform and in the means whereby they are automatically disposed of beneath the movable platform when the latter is lowered to the deck of the car for use as an ordinary freight car.

Other advantages and improvements will hereafter appear.

In the drawings accompanying this specification: Figure 1, is a partial side elevation and central vertical section of a car embodying my invention. Fig. 2, is a side elevation of a fragmentary detail of the car with a hog door in position beneath the movable platform. Fig. 3, is a plan view of the frame of the car and the manually rotatable shaft and connecting elements for raising or lowering the movable platform. Fig. 4, is a cross-sectional view through the car with the platform raised and supported upon the swinging brackets pivoted to the frame, and the hog doors suspended from the adjustable platform in position to close the openings through the side of the car below the platform. Fig. 5, is a like cross-sectional view, with the movable platform lowered to the floor of the car and the hog door disposed of beneath the platform. Fig. 6, is a side elevation of the manually operated ratchet lever for rotating the shaft controlling the raising and lowering of the platform. Fig. 7, is a view at right angles to Fig. 6 with parts in section. Fig. 8, is a perspective view of one of the swinging brackets upon which the platform rests when elevated.

Referring now to the letters of reference placed upon the drawings:—A, denotes a freight car.

B, indicates a relatively short shaft extending longitudinally within the car and supported by suitable hangers B', adjacent to the roof timbers C.

b, b', respectively indicate a right and a left hand screw-thread formed on the ends of the shaft B.

C, C', are traveling arms fitted to the screw threaded ends of the shaft.

D, D', are cables guided and supported by the sheaves E, E', connected with the arms C, C', and with the movable platform F. If desired additional cables D^a, passing over sheaves E^a, may be connected with the

traveling arms C, C', and with the sides of the platform as indicated in dotted lines in Fig. 3, thus providing an additional support to insure against the platform sagging under a heavy load.

H, H, indicate a pair of rods attached to the frame of the adjustable platform opposite the side door openings of the car.

I, indicates a hog door suspended from the rods by a cross rod I^a having eyes at each end to receive the rods H, H.

I', I' are metallic straps or battens, secured to the door with an eye at the top of each batten to receive the cross rod I^a. Thus 15 the hog door has a swinging connection with the rod I^a and a sliding connection with the rods H, H.

I², is a member hinged to the bottom of the hog door at i.

I³ is an angle iron secured to the member I², adapted to be engaged to the frame of the door opening by means of which the lower end of the hog door is held in position.

J, denotes a plurality of swinging brackets pivoted to the upright members of the car frame on each side of the car which are severally adapted to support the adjustable platform when in its elevated position, the 25 several brackets on each side of the car being connected together by means of a bar K, attached to the projecting lugs j, of the brackets, whereby the brackets on each side of the car may be simultaneously turned to 30 support the platform or tilted backward in order that the platform may be lowered to 35 the floor of the car.

j', are upstanding fingers formed on the ends of the side walls of the bracket which 40 overlap the edge of the channel iron or sill of the adjustable platform when the latter rests upon the brackets thereby linking the platform and the side walls of the car together to provide against the spreading of 45 the side walls as a result of the weight carried by the platform. It will be noted upon reference to Fig. 8, that the brackets are U-shaped in form and are adapted to embrace three sides of the upright members of the 50 frame, the closed end J' of the bracket bearing against the edge of the upright member of the frame when the sill of the adjustable platform rests on the portion J² at the opposite end of the bracket.

J³ is a latch hinged to the brackets adapted to bear against the car frame to maintain the projecting end of the brackets out of the path of the adjustable platform, that the platform may be lowered to the floor of 60 the car as indicated in Fig. 5;—the latches being swung back when the brackets are tilted forward to support the platform as indicated in Fig. 4.

L, is a lever adapted to manually rotate 65 the shaft B provided with a ratchet wheel

L', actuated by a double arm dog L², pivoted at L³, adapted to rotate the shaft in either direction as may be required.

L⁴ is a V-shaped spring actuated pin or tumbler, designed to hold the dog in position to engage the ratchet wheel—the operation of which will be obvious—when rotating the shaft in either direction.

Having indicated the several parts by reference letters the construction and operation of the device will be readily understood.

When employed as an ordinary freight car the adjustable platform rests upon the floor of the car. To adapt the car for carrying small stock, the adjustable platform is raised by the manual rotation of the shaft B, carrying the traveling arms C, C' to which the platform is attached by the cables D, D'. When in position the swinging 85 brackets J are lowered by the connecting bar K so that the sill of the adjustable platform rests upon the upper edge J² of the brackets, in which position the fingers j' of the brackets overlap the edge of the platform 90 sills thereby locking the side walls and the adjustable platform of the car together. In loading the car, the stock is driven into the lower compartment first and when filled the hog door I is pulled forward and swung 95 into the position indicated in Fig. 4, the bottom of the door being secured to the door frame by a suitable fastening device I³, thus insuring against the escape of the stock while loading the upper platform. When 100 the car is used for ordinary freight the hog door may be folded up between the adjustable platform and the floor of the car, and thus protect it from injury.

I do not wish to limit myself to the exact 105 means for suspending the hog door to the adjustable platform or the particular fastening device for securing the lower end of the hog door to the frame of the car as these are details which may be varied without departing from the spirit of my invention. 110 The principal object being to provide a small door designed to close the opening beneath the adjustable platform while loading the adjustable platform with other stock, 115 the arrangement being such that the door may be disposed of between the adjustable platform and the floor of the car when used for ordinary freight that it may be protected from injury.

Having thus described my invention what I claim is:

1. In a car, a relatively short rotatable shaft suitably journaled and centrally located within the car having right and left hand screw threaded portions, an arm fitted to each screw threaded portion of the shaft adapted to be moved either toward or away from each other upon the rotation of the shaft, a movable stock supporting platform 12

- designed to rest upon the floor of the car when not in use, cables suitably guided and supported connecting the arms with the movable platform, and manually actuated means located within the car and carried by the shaft adapted to rotate the latter in either direction, whereby the platform may be raised or lowered.
2. In a car of the character described, a body having a door opening therein, a vertically movable platform within the car body, means for supporting, raising and lowering the platform, rods carried by the platform adapted to support stock doors, and means adapted to slidably hinge the stock doors to the rods carried by the platform, whereby the doors may be folded under the platform upon lowering the latter to the floor of the car body.
- 10 3. In a car of the character described, a winding shaft, a platform connected with said shaft, means for rotating the shaft to raise or lower the platform, and a plurality of U-shaped brackets hinged to vertical members of the car body and adapted to be rocked into position to receive and support the platform when raised, or out of the path of said platform, whereby the platform may be lowered to the floor of the car.
- 20 4. In a car of the character described, a rotatable shaft, a platform connected with the shaft, means for rotating the shaft to raise or lower the platform, a plurality of U-shaped brackets hinged to vertical members on opposite sides of the car body, the brackets for each side being connected together to operate as a unit, whereby they may be collectively rocked into position to support the platform when raised, and shifted out of the path of the platform that it may be lowered.
- 25 5. In a car of the character described, a rotatable shaft, a platform frame connected

with the shaft, means for rotating the shaft to raise or lower the platform frame, a plurality of U-shaped brackets hinged to and partially surrounding members of the car frame and adapted to support the platform frame when raised, said brackets being adapted to engage the platform frame, whereby the platform and walls of the car are linked together to provide against spreading of the car walls due to the load carried by the car.

45 6. In a car of the character described, a rotatable shaft, a platform frame connected with the shaft, means for rotating the shaft to raise or lower the platform frame, a plurality of brackets hinged to and embracing vertical members of the car frame having projecting arms adapted to support the platform frame when tilted into the path of the latter, and a swinging latch carried by each of the brackets to support the latter out of the path of the platform frame, whereby it may be lowered or raised.

50 7. In a car of the character described, a rotatable shaft, a platform frame connected with the shaft, means for rotating the shaft to raise or lower the platform frame, a plurality of brackets hinged to the car frame having projecting arms adapted to support the platform frame when tilted into the path of the latter, and means comprising a latch hinged to each of the brackets adapted to bear against the car frame to support the brackets out of the path of the platform frame, whereby it may be lowered or raised.

55 75 In testimony whereof, I sign this specification in the presence of two witnesses.

JOHN BELL SHELTON.
